UNITED STATES PATENT OFFICE.

FRANCIS E. D. ACLAND, OF LONDON, LOUIS SILVERMAN, OF CRAYFORD, AND BENJAMIN ORMAN, OF DARTFORD, ASSIGNEES TO THE MAXIM-NORDENFELT GUNS AND AMMUNITION COMPANY, LIMITED, OF LONDON, ENGLAND.

APPARATUS FOR FILLING CARTRIDGE FEED-BELTS FOR MACHINE-GUNS.

SPECIFICATION forming part of Letters Patent No. 536,591, dated April 2, 1895.

Application filed May 18, 1892. Serial No. 433,437. (No model.)

To all whom it may concern:

Be it known that we, FRANCIS EDWARD DYKE ACLAND, late captain royal artillery, a resident of Victoria Street, Westminster, London, LOUIS SILVERMAN, engineer, a resident of Crayford, Kent, and BENJAMIN ORMAN, engineer, a resident of Dartford, Kent, England, subjects of the Queen of Great Britain, have invented certain new and useful Improvements Relating to the Filling or Charging of Feed Belts or Bands for Supplying Guns with Cartridges and to Apparatus Therefor, of which the following is a specification, reference being had to the accompanying drawings.

This invention has reference to improvements relating to the filling or charging of feed belts or bands for supplying guns with cartridges and to apparatus therefor. Such belts or bands are usually made of two strips or webs of canvas or similar material, firmly united at intervals in such manner as to leave apertures between the strips or webs for the reception of the cartridges. Heretofore these belts or bands have been filled or charged by taking up the cartridges by hand, one by one, and pushing them successively into the aperture in the belt or band. This is a very tedious process, chiefly by reason of the difficulty of separating the two strips or webs of material to admit the cartridges. Moreover the belt or band cannot be conveniently held by one hand while the cartridges are inserted by the other hand, and consequently the filling or charging of the said cartridge belts has hitherto involved the expenditure of a considerable amount of time and labor.

The present invention resides in an improved automatic mechanism for giving the belt or band an intermittent movement between suitable guides, and, during each interval between the successive feed movements thereof, inserting a pin or pointed rod into one of the apertures in the belt or band to separate the two strips or webs thereof, and then withdrawing the said pin or pointed rod

from the said aperture and simultaneously inserting a cartridge therein.

The said machine for the purpose above specified will now be described with reference to the accompanying drawings, in which—

Figure 1 is a side elevation of the principal parts of the said machine. Fig. 1^a is a central vertical section of the same on line x'-x' of Fig. 2. Fig. 2 is a top plan view of the mechanism of Fig. 1. Fig. 3 is an end view of Fig. 1 viewed from the right hand end of the same. Fig. 3^a is a sectional view taken on line y'-y' in Fig. 2. Fig. 4 is an elevation of the machine viewed from the opposite side to that which is shown in Fig. 1. Fig. 5 is an elevation of a cartridge hopper forming part of the machine and hereinafter more particularly described. Fig. 6 is a plan of Fig. 5. Fig. 7 is a vertical section on the line x-x of Fig. 5. Fig. 8 is a sectional plan on the line y-y of Fig. 5. Fig. 9 is an underside view of an alternative form of machine, and Fig. 10 is an end view of Fig. 9. Fig. 11 is a view of part of Fig. 10 in another position.

A is the body of the machine. A' is an extension therefrom in which the screw B is mounted, so that the machine may be clamped to any convenient support adapted to be engaged between the head B' of the screw and the portion A² of the body of the machine.

C is a bar which slides endwise in bearings in the body A.

D is a handle fixed to a short shaft E which turns in a bearing A³ provided upon the body of the machine. F is a crank connected at one end to the said short shaft E and at the opposite end to the bar C by the connecting rod G.

H is a pointed rod secured to one end of the bar C in such a manner that the greater portion of its length lies parallel thereto and I is a push piece secured to the opposite end thereof. The former is for the purpose of separating the two strips or webs of the cartridge belt or band, and the latter for pushing cartridges into the apertures so formed.

J is a spindle which turns in bearings in the upper part of the body A. K is a ratchet wheel and L is a collar, both of which are firmly secured to the said spindle.

5 M and N are wheels which in the present instance are formed in one piece with the collar L, the said wheels being provided with teeth M' and N' respectively, to gear with the cartridges in a manner hereinafter explained 10 as they are placed in the belt. The spaces between the teeth M' are made wider than those between the teeth N' in order to receive tags which project from one side of the cartridge belts used with the Maxim gun, for example.

15 O is a pawl, jointed at O' to one end of a lever P. The said lever turns upon a fulcrum screw Q on the body A and carries at its opposite end an antifriction roller P' which runs 20 on the under side of the bar C and in a suitably shaped groove C' formed therein. The said pawl O engages with the ratchet wheel K, and is maintained in engagement therewith by the spring O² which is secured at one 25 end to the pawl, and at the other end to the body A.

Q' Q' are parallel guides grooved as at Q² to receive the opposite ends of the cartridges, as shown in Fig. 4. R is a channel between the 30 said guides through which the cartridge-belt or band passes, below a bridge piece S. The bottom of the channel is curved at the ends as shown at R' R², so that the cartridge belt or band may enter and leave the said channel 35 easily.

R³ is a raised portion of the floor of the channel, provided at the end thereof at which the cartridge-belt or band enters, so that the space between the floor of the channel and the under side of the bridge-piece S is narrowed 40 for a purpose to be hereinafter explained.

T is a cartridge belt or band and T' are the cartridges.

45 U is the hopper from which cartridges are delivered to the belt charging mechanism in a manner which will be herein explained. The said hopper has curved and inclined sides so that when cartridges are dropped into it they 50 are of such dimensions that a cartridge can only pass therethrough when its rim is above the notches U².

The hopper is supported by a standard V provided with flanges V' which extend to 55 within a short distance of the bottom of the standard and are undercut or grooved as shown at V² in line with the notches U² to receive the rim of cartridges which pass through the opening U'. At the foot of the said standard V is a tray W with side walls W'. The said tray is slotted at W² as shown, and is provided with a circular opening at its rear and with a lateral extension W³ by which the standard V and its appurtenances are secured 60 to the machine.

The operation of the said machine will now be explained.

The end of the cartridge belt or band is passed by hand into the channel R at R' and below the bridge-piece S, between which and the bottom of the raised portion R³ of the channel the belt fits with sufficient tightness to prevent it from slipping back. The first loop or aperture between the two strips or webs of the cartridge-belt or band is brought 70 by hand into line with the pointed rod H, which, by moving the bar C by means of the handle D, crank F and connecting rod G, is forced into the said loop. The hopper U is now charged with cartridges, which fall successively through the opening U', the rims of the cartridges passing through the notches U² into the grooves V², in which they slide downward. The lowermost cartridge comes to rest 75 in the tray, W and opposite the circular opening thereof with its rim clear of the flanges V'. In this position the said lowermost cartridge is in front of the push piece I, which when the pointed rod H is right home in a loop of the cartridge belt is always clear of the standard V and the cartridges therein. If now the movement of the crank be continued 80 the bar C will be moved to cause the push piece I to enter the tray W by the said circular orifice and force the lowermost cartridge 85 before it into the loop of the cartridge belt, the movement of the said bar simultaneously withdrawing the pointed rod H from the loop. In the drawings the bar C is shown at half stroke and in Fig. 1 the pointed rod H is in the position it would occupy when withdrawing 90 from a loop of the belt while the push piece I forces a cartridge thereinto. The cartridge next above the lowermost one bears 95 upon the top of the push piece I as shown, 100 while that push piece is moving toward the belt, and when the push piece has completed its return movement away from the belt, drops down in front of the said push piece, by which it is in turn moved forward, and so on.

The movement of the cartridge belt, in order to bring loops thereof successively into line with the pointed rod H and push piece I, is effected automatically, in the following manner: When a cartridge is inserted in the belt its opposite ends lie between the teeth of the wheels M and N as shown in Fig. 4, and, during the time that the pointed rod H moves toward the said wheels from its extreme position, the action of the inclined portion of the groove C' on the antifriction roller P' moves the lever P and thereby causes the pawl O to rotate the ratchet wheel K and with it the spindle J and the wheels M and N. The teeth of the wheels M and N act upon the cartridge 115 which lies between them and move the belt a sufficient distance to bring the next loop thereof into position to receive a cartridge. The frictional resistance to the movement of the belt in the narrow channel below the 120

125 standard V and the cartridges therein, and the 130

bridge piece S enables the wheels M and N to keep the belt taut and maintain it at the proper level in the channel R. The inclined groove C' is so situated upon the bar C that movement of the lever P, and consequently of the spindle J, ceases when the head of the pointed rod H arrives within a short distance of the wheel M. When the pointed rod H is withdrawn from the cartridge belt to its extreme position, the antifriction roller P rises into the groove C' and causes the lever P and pawl K to move into position in readiness to be again operated in the manner above described. The direction of the movement of the feed belt is indicated by the arrows in Fig. 3.

We wish it to be clearly understood that we do not limit ourselves to the particular form of the machine hereinbefore described with reference to the drawings. By way of example, the bar C may be operated by means of a lever instead of by a crank and connecting rod. Cartridges may be placed in the tray W by hand if desired, but the employment of a hopper is preferable.

Instead of the bridge piece S a spring arm may be used for keeping taut the belt during the insertion therein of the pin or pointed rod and of the cartridge. This arm is so arranged that it will yield to permit the feeding of the belt as required.

In Figs. 9, 10 and 11 an alternative form of machine is shown, wherein the feeding of the belt through the machine is effected by means of the pointed rod which opens out the spaces in the belt to receive the cartridges. On the end of the bar C opposite the push piece is rigidly secured a link C² which is in turn attached to a rod C³ by means of a collar. The said rod C³ is arranged to slide endwise in bearings A⁴ and is also capable of rotation on its axis in the said bearings. To the end of the rod C³ is secured a short arm H' which carries the pointed rod H for opening the belt.

C⁴ is a pin tightly secured in the bar approximately at right angles thereto.

A⁵ A⁶ are projecting parts of or pieces firmly secured to the frame A and provided with grooves a, a' in which the ends c, c' of the pin C⁴ can slide. At the end of the said parts A⁵ A⁶ are formed or fixed two cam pieces A⁷, A⁸, provided with inclined surfaces a², a³, as shown.

X is a serrated retaining pawl having a groove X' on the face over which the cartridge belt is passed and which is attached by a strong spring X² to the base A. Another spring X³ is arranged to press the belt on the top or grooved face of the said pawl X and thus to retain the said belt in position level with the rod H.

A hopper of similar pattern to that hereinbefore described is shown in place in Fig. 10.

The operation of this form of machine is as follows: The cartridge belt is passed between the spring X³ and the pawl X, and is adjusted

by hand to bring the first loop opposite to the pointed rod H, the latter having been moved to its rearmost position clear of the belt. The short arm H' is then in the position shown in Fig. 10 and the end c of the rod C⁴ is opposite the end of the groove a of the piece A⁵. The hopper is now charged with cartridges and the handle D rotated causing the rod H to enter and open out the loop in the belt. When the bar C³ is nearly at the end of its stroke the end c of the rod C⁴ strikes the inclined surface a² of the cam piece A⁷ and rotates the bar C³ on its axis till the end c' of the rod C⁴ is opposite the groove a' of the piece A⁶. This rotary movement causes the link H' to take the position shown in Fig. 11 thus feeding the belt on into position for the cartridge to be inserted. On the rotation of the handle being continued, the pointed rod H is withdrawn from the belt and a push piece arranged and operating in a manner similar to that described with reference to the push-piece I in Fig. 1 closely follows the rod H and forces home a cartridge into the belt. When the bar C³ has nearly reached the other end of its stroke and the cartridge is nearly home the transverse rod C⁴ strikes the inclined part a³ of the cam piece A⁸ and this rotates the rod C³ backward until the pin H is brought in line with the pawl X again. As the handle is further rotated the pin H enters the next loop of the belt, opens it and feeds the belt on for the next cartridge to be forced in.

The machine may be operated either by hand or by steam or other power as may be most suitable.

What we claim is—

1. In a machine for filling cartridge belts, the combination with guides between which the cartridge-belt passes, of a rod supported and movable at right angles to the said guides and adapted in its movement to enter between the two webs of the said belt to open the same, a push piece movable in line with the said rod for forcing the cartridges into the belt, and mechanism for giving the belt an intermittent movement through the guides, as set forth.

2. In a machine for filling cartridge-belts the combination with guides between which the cartridge belt passes of feed wheels notched or toothed to engage with the cartridges in the said belt, a ratchet-wheel adapted to rotate with the said feed-wheels, a pawl by which the said ratchet-wheel is operated, carried upon a lever and a reciprocating bar formed with an inclined surface whereby the said lever is vibrated, substantially as described.

3. In a machine for filling cartridge-belts the combination of guides between which the cartridge-belt passes, a reciprocating bar having a pointed rod to open the belt and a pusher to force the cartridge home and a hopper U

having an opening U' conforming to the shape of the cartridges, and a standard V grooved at V' to receive the rims of the cartridges substantially as described.

5. 4. In a machine for filling cartridge belts the combination with the guides Q, the raised portion R³ of the floor of the channel R and the bridge piece S substantially as hereinbefore described for the purposes set forth.

In testimony whereof we have hereunto signed our names in the presence of two subscribing witnesses.

F. E. D. ACLAND.
LOUIS SILVERMAN.
BENJAMIN ORMAN.
